DESIGN FOR A PERFUME DISPLAY CASE

Joseph Miller, New York, N. Y.

Application July 25, 1941, Serial No. 102,479

Term of patent 3½ years

To all whom it may concern:

Be it known that I, Joseph Miller, a citizen of the United States, residing at New York, in the county of New York, city and State of New York, have invented a new, original, and ornamental Design for a Perfume Display Case, of which the following is a specification, reference being made to the accompanying drawing, forming a part thereof.

Fig. 1 is a perspective view of a perfume display case embodying my new design; and
Fig. 2 is an end view thereof.

The back of the display case is flat and unornamented.

I claim:

The ornamental design for a perfume display case, substantially as shown and described.

JOSEPH MILLER.
